UNITED STATES PATENT OFFICE.

FREDERICK E. HAPPEL, OF BALLSTON, VIRGINIA.

COMB CLEANER.

Application filed March 20, 1922. Serial No. 548,154.

To all whom it may concern:

Be it known that I, FREDERICK E. HAPPEL, a citizen of the United States, residing at Ballston, county of Alexandria, Virginia, 5 have invented a new and useful Comb Cleaner, of which the following is a specification.

The object of my invention is to provide an efficient comb cleaner which can be adjusted for use with different sizes of combs, and to provide a device which can be manufactured at relatively small cost. I attain these and other objects of my invention by the mechanism illustrated in the accompanying drawings, in which:—

Figure 1 is a perspective view of the invention;

Fig. 2 is an end elevation of same;

Fig. 3 is an edge elevation looking in the 20 direction of the arrow;

Fig. 4 is a horizontal section on line 4—4 of Fig. 2;

Fig. 5 is a detail vertical section on line 5—5 of Fig. 2;

Fig. 6 is a perspective view of my invention provided with means for mechanically operating the end plates simultaneously; and

Fig. 7 is a transverse section on line 7—7 of Fig. 6.

Like numerals indicate like parts in each of the several views.

Referring to the accompanying drawings, I provide a suitable frame holder or handle 1 stamped preferably of metal and of proper 35 shape to be easily held in the hand and strong enough to withstand the tension of the cleaning tape or cord 14. Handle 1 is provided with end frame members 2 having the elongated slots 3 through which the tape

40 or cord 14 passes. End frames 2 terminate in reversely bent ends 4 which in turn terminate in reversely bent hooks 5 to which the ends of the cord or tape 14 are fastened, as shown in Fig. 2. I provide end plates 6 having vertical edge portions 13 which are engaged by the reversely bent ends 4 and are vertically slidable. The reversely bent ends 4 are provided with depressions 10 which releasably engage spaced depressions 9 in the

45 vertical edge portions 13 of the end plates 6. The end plates 6 have their main portion disposed in a downwardly and outwardly slanting relation relative to the upright portion of the U-shaped handle or holder 1, as shown in Figs. 1 and 3.

I provide a series of converging slots 7 in

the end plates 2, these slots having enlarged openings 8 at the top of each slot for the convenient threading of the tape through same. The end plate 6 may be made of any suitable 60 material, such as metal or celluloid and can be stamped out. The spacing of the slots 7 at the top of the plate is equal in width to the separation of the teeth of the coarsest comb, and converge so that at the bottom 65 they will be spaced close enough to correspond to the spacing of the teeth of a fine comb.

In use, the cleaning tape or cord is threaded through the openings 8 from one end plate 6 to the other plate and the ends of the cord finally secured to the hooks 5, as shown in Fig. 2. To adjust the spacing of the tape to suit it for use to the particular comb to be cleaned the end plates 6 may be raised or 70 lowered relative to the end holder frame members 2, and as the tape or cord 14 passes through the slots 3 in members 4 it will accordingly be adjusted in the slot 7. The end plates slant outwardly, as shown in Figs. 1 80 and 3, from their top edges 11 to their lower edges 12 to a sufficient extent to equal the change in adjustment of the tape or cord 14 from its arrangement in more widely spaced portions of the upper ends of the slots 7 to 85 the more narrowly spaced portions of the lower ends of said slots. The depressions 10 will make it easier to hold the holder 1 while shifting the end plates 6 up or down to adjust the space of the cord or tape 14 to suit 90 the spacing of the comb which is to be cleaned.

Referring to Figs. 6 and 7, I may provide suitable means for mechanically raising and lowering the end plates simultaneously, and 95 for this purpose provide supporting members 15 in which is rotatably mounted rod 16 having a suitable handle 17. Rigidly attached to the rod 16 in proximity to the end plates 11 I provide bars 18. I further provide links 20 connecting the ends of bars 18 by pivots 19 with the central bottom portions of end plates 6 by means of pivots 21.

In operation, rotation of the handle 17 and rod 16 will lower bars 18 and links 20 105 and pull the end plates 6 downwardly; a reverse action will elevate the end plates.

What I claim is:—

1. In a comb cleaner, the combination of an approximately U-shaped holder having 110 opposite slotted end frames, end plates, said end plates having converging slots extend-

ing from top to bottom, means for adjustably mounting the end plates in the holder and frames, and a tape and cord threaded through the slots in the end plates and also 5 through the elongated slot in the holder end frames.

2. In a comb cleaner, the combination of a holder, end frame members in which said holder terminates, said members having like 10 horizontal slots, said end frame members also having reversely bent end portions, end plates engaged by the reversely bent ends and vertically slidably, said plates having converging slots, the main portion of the 15 plate being shaped to slant outwardly in the direction in which the slots in said plates converge.

3. In combination with the apparatus described in claim 2, series of spaced depressions in the side portions of the end plates, and depressions in the reversely bent portion of the holder and frames to releasably engage the depressions in the end plates for convenience in holding and adjusting same.

25 4. As a new article of manufacture for a device of the class described, an approximately U-shaped holder having elongated end frame members, each of said end frame members having elongated slots through 30 which a cord may be threaded, the end frame members also having opposite reversely bent ends to engage and hold the end frame members in adjustable relation to the U-shaped holder, and said ends in turn having 35 depressions to function as snap fastener members.

5. In a comb cleaner, the combination of a holder, end plates vertically slidable in said holder, the end plates having a series of 40 converging slots, a tape or cord threaded through said slots, means for adjusting the height of the end plates relative to the holder, and means for retaining the tape or cord in a predetermined relation to the 45 holder regardless of the position relative to the holder of the end plates.

6. In a comb cleaner, the combination of a holder, end plates vertically slidable in said holder, the end plates having a series of 50 converging slots, a tape or cord threaded through said slots, means for adjusting the

height of the end plates relative to the holder, and means for retaining the tape or cord in a predetermined relation to the holder regardless of the position relative to 55 the holder of the end plates, said end plates having their slotted portion disposed in a slanting position relative to the holder, the outward slant of the plates being sufficient to equalize the difference in spacing of the 60 converging slots so that the tape or cord will remain taut in all adjustments of the end plates relative to the holder.

7. In a comb cleaner, a holder having slotted end frame members, said end frame 65 members having reversely bent end portions, said reversely bent end portions having reversely bent hooked ends functioning as cord-holding members, end plates adjustably mounted in the end frames, said end plates 70 having converging slots, and a tape or cord member threaded through said slots and through the slots in the holder end frames.

8. In combination with the apparatus described in claim 2, means for mechanically 75 raising and lowering the end plates simultaneously.

9. In combination with the apparatus described in claim 6, means operatively connected with each of the end plates and including a common operating handle for simultaneously raising and lowering both 80 end plates.

10. In a comb cleaner, a holder, slotted end frame members oppositely positioned in 85 which the holder terminates, said end frame members having reversely bent ends, end plates vertically slidable in said bent ends, each of the end plates having converging 90 slots, a tape or cord threaded through the slots in the end frame members and through the converging slots, in the end plates, means for securing the ends of said cord or tape to the end frame members, links pivotally attached to the central portions of the 95 bottom of the end plates, bars to which said links in turn are pivotally attached, a rod to which both of said bars are rigidly affixed, means attached to the holder for rotatably supporting said rod, and an operating 100 handle for said rod.

FREDERICK E. HAPPEL.
